UNITED STATES PATENT OFFICE.

GEORGE R. DELAMATER, OF STEELTON, PENNSYLVANIA.

MINERAL SAMPLER.

1,414,726.

Specification of Letters Patent. Patented May 2, 1922.

Application filed October 22, 1919. Serial No. 332,545.

To all whom it may concern:

Be it known that I, GEORGE R. DELAMATER, a citizen of the United States, residing at Steelton, in the county of Dauphin and State of Pennsylvania, have invented certain Improvements in Mineral Samplers, of which the following is a specification.

This invention is an automatic sampler adapted to be operated at regular intervals 10 to segregate portions of the materials under examination by intersecting a flowing stream thereof. It is applicable to use for sampling crushed coal, rock, ore, sand or other flowing solids, as also liquids that are 15 not of such viscous or adhesive character as to build up in the apparatus.

The objects attained by the invention are the desiderata of separating samples not only from the full cross section of a flowing stream, but also from a column falling vertically, with the segregation of representative samples, and the avoidance of the possibility of mixing the samples with the main flow, by means that are simple and efficient.

25 The invention is characterized by a hollow body or case provided with an inlet in the top thereof for the admission of a substantially vertical stream of materials which are to be sampled, a throat (of substantially the 30 width of the body) adapted to oscillate across the inlet so as to fully intersect a stream flowing therethrough, a chute having an inlet below the bottom of the throat and an outlet through a side of the body, detachable wings connected with the sides of 35 the throat at the top thereof and extending outwardly over the passage between the throat and the chute, and an outlet in the bottom of the body or case for discharging 40 the main flow of the material in process of sampling.

The characteristic features of the invention are embodied in the mechanism set out in the following description and the accompanying drawings in illustration thereof.

In the drawings, Fig. 1 is a side elevation 50 of a sampler embodying my invention; Fig. 2 is a vertical sectional view thereof; Fig. 3 is a vertical sectional view taken on the line 3^x-3^x of Fig. 2; Fig. 4 is a side elevation of detached oscillating mechanism of modified form, and Fig. 5 is a sectional view taken on the line 5^x-5^x of Fig. 4.

The sampler, illustrated in Figs. 1 to 3 55 inclusive, comprises a hollow body or case 1 provided with a centrally disposed top in-

let 2 having substantially the width thereof and an outlet 3 directly below the inlet, the body expanding in opposite directions from the inlet and the outlet. 60

A throat 4, having substantially the width of the body 1, is connected by its transverse downwardly extending members 5 and 6, with the respective trunions 7 and 8, which are journaled in bearings 9 and 10 supported by the body, the throat having a contracted bottom outlet 11. 65

A chute 12, provided with the angles 13, is supported in the body 1 by the angles 14 therein on which rest the angles 13. The 70 chute has an open top adapted to receive the discharge from the bottom of the throat, which oscillates therein, is provided with flared top members 15 for permitting the full swing of the throat within a limited 75 width of chute, has its ends covered by the plates 5 and 6 extending downwardly from the throat and has an inclined outlet 16 extending through the side of the body. 80

Wings or aprons 17 are connected by their 85 hooks 18 with the sides of the throat 4 at the top thereof, and are connected together by the parts 5 and 6 extending transversely thereto, the wings diverging downwardly beyond the bottom of the throat and the top 90 of the chute so that the inclined wing directly below the inlet 2 will pass materials falling thereon beyond the chute. These plates 17, over which the bulk of the materials slides, are made detachable in order 95 that they may be replaced in case of wear.

Inwardly inclined wings 19 extend across the sides of the body 1 above the ends of the throat 4 to cover the joints between such ends and body. 95

The throat 4, with the wings thereon, is oscillated at regular intervals, by any usual means applied to the shaft 7, through its full arc, which is limited by contact of the bottom of the throat with the wings 15 at the 100 top of the chute 12. The top of the oscillating throat passes transversely through the stream of the material, such as ore or coal, falling vertically thereto through the opening 2, and segregates a full cross sectional 105 and characteristic part thereof, which is delivered through the bottom of the throat to the chute 12 and thence discharged by the outlet 16 through the side of the body 1.

As illustrated in Figs. 4 and 5, the oscillatory mechanism may be modified, so as to 110 reduce the amount of the sample segregated

at each oscillation, by reducing the inlet to the top of the modified throat 4' by dividing its top as also the tops of the inclined wings 17' and providing intersecting inclined auxiliary wings or aprons 17" in the notches 4^a and 17^a formed thereby, these intersecting inclined planes 17" providing means for diverting part of the substance under treatment from the throat 4' and reducing the 10 amount passing therethrough.

The case 1 is provided with the removable plate 20 having the bearing 9 and the chute extension 21 thereon, the oscillatory mechanism and the chute being removable from 15 the case therewith.

Having described my invention, I claim:

1. In mechanism of the character described, the combination with a case having an inlet in its top and an outlet in its bottom, 20 of a throat having an inlet of substantially the width of said inlet first named, means for oscillating said throat in said case to cause its inlet to sweep across said inlet first named, means for discharging minerals from 25 said throat through said case, and diverging wings carried by said throat, said wings adapted at the limits of their movements to extend across said inlet first named and intersect alternately the stream of materials 30 flowing therethrough.

2. In mechanism of the character described, the combination with a case having top and bottom apertures, said case expanding from said apertures, of an oscillatory 35 throat having an open top adapted to sweep across said top aperture so as to be out of registration therewith, inclined plates extending oppositely from the top of said throat, so as to chute materials from said top

aperture to said bottom aperture and a chute 40 to which said throat discharges, said plates covering the joint between said throat and chute.

3. In mechanism of the character described, the combination with a case having a detachable side member, a top inlet and a bottom outlet, of an oscillatory conduit in 45 said case, said conduit having a bearing carried by said member and removable from said case by detaching said member.

4. In mechanism of the character described, the combination with a case having a detachable side member, a top inlet and a bottom outlet, of an oscillatory conduit and a chute in said case, said conduit and chute 55 being removable from said case by detaching said member.

5. In a machine of the character described, the combination with a case having an inlet, of an oscillatory conduit in said 60 case having an inlet adapted to sweep across materials flowing through said inlet first named, and diverging aprons carried by said conduit, said aprons being movable with said conduit alternately under said inlet first 65 named so as to receive the materials passing therethrough.

6. In a machine of the character described, the combination with a case having an inlet, of an oscillatory throat having inlets adapted to cut across materials flowing 70 through said inlet and inclined members connected with said throat so as to be movable thereby beneath said inlet and chute materials passing therethrough.

In testimony whereof I have hereunto set my name this 11th day of October, 1919.

GEORGE R. DELAMATER.
